ABSTRACT OF THE DISCLOSURE

A bi-directional ring counter comprises a plurality of silicon controlled switching stages. An input pulse causes an RC circuit to charge through a path which is determined by the selective energization of either an add or a subtract bus. The direction of the charging current effects the desired direction of counter operation.

The present invention relates to electronic counters and to be more specific to a ring counter which is able to operate in both the add and subtract mode.

A ring counter is an electronic circuit which, for each input pulse, some information is moved one step along a series of stages. A ring counter in the add mode would move the information along the stages in one direction while in the subtract mode would move it in the opposite direction. When the number of pulses supplied to the ring counter is sufficient such that the information is in its last stage, the next succeeding pulse causes the counter to register information of this fact in a succeeding counter and to become reset for another series of pulses.

It is an object of this invention to provide a relatively simple counting circuit which may be operated in either the add or subtract mode.

A more particular object is to provide a reversible ring counter utilizing a gate controlled bistable semiconductor switching element in each stage.

This result is achieved in a circuit in which each stage includes a silicon controlled switch and a set of steering diodes. Depending on whether the add or subtract mode has been selected, a selected voltage storage device charges during a count pulse thereby drawing current in a certain direction. If the ADD mode has been selected this current develops a voltage across a resistor in the gate circuit of a succeeding stage and alternately in the gate circuit of a preceding stage if the subtract mode has been set.

The subject matter which we regard as our invention is particularly pointed out and distinctly claimed in the appended claims. Our invention, however, both as to its organization and method of operation, together with further objects and advantages thereof, may best be understood by reference to the following description taken in connection with the accompanying drawings in which:

FIGURE 1 shows a circuit diagram of the ring counter of this invention; and

FIGURE 2 shows the anode-cathode circuit of one stage in another embodiment of this invention.

The embodiment of FIGURE 1 is shown with four silicon controlled switch (SCS) stages connected in cascade but this is merely exemplary and more or less stages may be added at will. Anode voltage is supplied to the SCS's S1, S2, S3, and S4 through a pair of resistors R1 and R2 from a source of positive voltage. In this case the anode supply voltage is shown to be a positive 24 v. D.C. but this is also merely exemplary. The capacitor C1 is connected from the junction of R1 and R2 to ground. The function of the resistor R1 and the capacitor C1 is for decoupling purposes so as to prevent random "turnons" of the SCS's when the anode voltage is first applied. The 24 v. D.C. supply is also connected through

2

resistors R3, R4, R5, and R6 to the respective gate electrodes of the switches S1, S2, S3, and S4. Resistors R7, R8, R9, and R10 are connected in series with lamps N1, N2, N3, and N4 in the anode-cathode circuits of the SCS's S1, S2, S3, and S4 respectively. The anode gate electrode of each SCS is connected through a series circuit comprising a diode and a capacitor to both the cathode of the last preceding SCS and the next succeeding SCS. To illustrate, at the junction of R4 and the anode gate electrode of S2, diode D2 and capacitor C3 are connected in series to the junction of R7 and the cathode of S1. Also at the junction of R4 and the anode gate of S2, diode D6 and capacitor C9 are connected in series to the junction of R9 and the cathode of S3. There are similar connections for each stage. Thus, at the junction of R5 and the anode gate electrode of S3, diode D3 and the capacitor C4 are connected in series to the junction of R8 and the cathode of S2. Also at the junction of R5 and the anode gate of S3, diode D7 and capacitor C10 are connected in series to the junction of R10 and the cathode of S4. At the junction of R6 and the anode gate electrode of S4, diode D4 and capacitors C5 are connected in series to the junction of R9 and the cathode of S3. Also at the junction of R6 and the anode gate of S4, diode D8 and capacitor C7 are connected in series to the junction of R7 and the cathode of S1. The cathode gates of S1, S2, S3, and S4 are connected to their respective cathodes.

Resistors R11 through R18 are connected across the capacitors C3 through C10 respectively and are used to control the charging and discharging rate of the capacitors. Diodes D9 through D12 connect a subtract (SUB) terminal to the respective junctions of the series combinations of diodes and capacitors which connect the anode gate electrodes of the SCS's to the last preceding stages. In like manner the diodes D13 through D16 connect an addition (ADD) terminal to the respective junctions of the series combinations of diodes and capacitors connecting the anode gate electrodes of the SCS's to the next succeeding stages. A transistor T1 has its collector-emitter circuit connected from the junction of the resistor R2 and the anodes of the SCS's to ground. A trigger pulse input terminal is connected through an input circuit comprising capacitor C2 and resistor R19 to the base electrode of the transistor T1. A "set count" terminal is shown connected through resistor R20 to the anode gate electrode of SCS S1; but it should be understood that this connection may be to the anode gate electrodes of any of the SCS's in the ring counter. The "set count" terminal can be connected to ground through a switch 20; however, any means of grounding the "set count" terminal will suffice.

The first step in the operation of the circuit of FIGURE 1, after the 24 v. D.C. supply has been applied, is to reset the circuit by momentarily grounding the "set count" terminal by momentarily closing the switch 20. This causes current to flow from the 24 v. D.C. supply through resistor R3 and resistor R20 to ground. The current flow through resistor R20 causes a negative voltage at the anode gate electrode of S1 with respect to its anode thereby turning it on. Conduction through S1 is indicated by the glow of the lamp N1 connected in the anode-cathode circuit.

The mode of operation is determined by applying a B⁺ potential to either the ADD or SUB terminal. With a 24 v. D.C. supply applied to the anodes of the SCS's, the preferred embodiment is to utilize a 24 v. D.C. potential for the B⁺. To illustrate the operation of FIGURE 1, the ADD mode will be first discussed.

In the quiescent state, before a trigger pulse is applied, the current flowing through the anode-cathode circuit of

S1 creates a voltage at the junction of the cathode of **S1** and the resistor **R7** which opposes the voltage at the ADD terminal and the voltage at the D.C. supply terminal. The voltage across capacitors **C7** and **C3** is thus very small and the charge on these capacitors is at a minimum. In this embodiment this quiescent state of minimum charge on capacitors **C7** and **C3** is typically developed approximately 25 micro-seconds after the initiation of conduction through **S1**. Since the remaining SCS's are in their non-conducting state, the voltage at the junction of their cathodes and their load resistors is approximately at ground potential. Therefore, the 24 v. D.C. supply causes the capacitors **C4**, **C5**, and **C6** to become fully charged to approximately 24 v. Similarly the 24 v. D.C. **B⁺** at the ADD terminal causes the capacitors **C8**, **C9**, and **C10** to become fully charged to approximately 24 v.

When a count is to be added, that is **S1** turned off and **S2** turned on, an input trigger pulse is applied to the transistor **T1**. This turns on **T1** and it quickly saturates thereby providing a shunt path for the current flowing in the anode-cathode circuit of **S1** so that the current of **S1** falls below its holding value and conduction of **S1** is halted. The magnitude of the trigger pulse necessary to turn the transistor **T1** on is determined by the input circuit comprising the capacitor **C2** and the resistor **R19** as well as the particular type of transistor selected. The minimum pulse width of the trigger pulse is determined by the charging time constant of the capacitors **C3** through **C10**. The time constant of these capacitors must be such that they have the ability to take additional charge when the trigger pulse is removed for purposes which will be more fully explained hereinafter. In a preferred embodiment the input trigger pulse must be at least one volt in amplitude and have a minimum pulse width of 30 microseconds.

With a trigger pulse applied the cessation of conduction through **S1** removes the voltage from **R7** thereby allowing the capacitors **C3** and **C7** to charge through the resistor **R4**, the diode **D2**, resistor **R7**, and lamp **N1** and through the diode **D16**, resistor **R7**, and lamp **N1** respectively. Since the charging time constants of the capacitors **C3** and **C7** are much longer than the duration of the input trigger pulse, these capacitors are still charging when the pulse is removed and the anode voltage is restored to the SCS's. The current building up charge on the capacitor **C3** causes a voltage drop across the resistor **R4** which holds the anode gate potential of **S2** negative with respect to its anode thereby turning it on. Since the capacitor **C7** charges through the diode **D16** instead of the resistor **R6**, the SCS **S4** remains in a nonconducting state. Conduction through **S2** causes the voltage at the junction of **R8** and the cathode of **S2** to approach 24 v. thereby driving the capacitors **C4** and **C8** to their minimum charge. **C4** discharges through **R12** and **C8** discharges through **R16**.

After the input trigger pulse is removed and anode voltage is restored to the SCS's, the approximately 24 v. charge on capacitors **C4**, **C5**, and **C6** oppose current flow through resistors **R5**, **R6**, and **R3** respectively thereby preventing turn on of SCS's **S3**, **S4**, and **S1** respectively. Thus, after the input pulse is removed, only **S2** is conducting. Conduction through **S2** turns the lamp **N2** on thereby adding a count to the ring counter.

When another count is to be added, another pulse is applied to the base of transistor **T1** and an operation similar to that described above is initiated. Thus, transistor **T1** saturates and the voltage at the anodes of all the SCS's is shunted to ground. **S2** ceases to conduct and the capacitors **C4** and **C8** begin to build up charge. Since the charging path of capacitor **C4** is through the resistor **R5**, diode **D3**, resistor **R8**, and lamp **N2**, a voltage is presented to the anode gate of **S3**. Since this voltage is negative with respect to the voltage at the anode, when the anode voltage is once again restored **S3** will conduct. The capacitors

C5 and **C9** will then begin to discharge, thus readying the circuit for another input pulse or count.

If the ring counter had been in the SUB mode, and SCS **S1** in the conducting state, the charging paths of the capacitors **C3** and **C7** would have been different. Capacitor **C3** would have charged through the diode **D10** the resistor **R7** and the lamp **N1** while capacitor **C7** would have charged through resistor **R6**, diode **D8**, resistor **R7**, and lamp **N1**. The voltage developed across resistor **R6** would create a negative voltage at the anode gate of **S4** which would be sufficient to turn **S4** on after its anode voltage has been restored. Thus one count would have been subtracted from the ring counter.

Inasmuch as all of the stages of the ring counter are alike, their operation is similar to the operation described. There is no limit to the number of stages that can be utilized, the only criterion being that one of the stages is "on" at any given time. The counting rate of the ring counter is limited by the values of the resistors **R11** through **R18** connected across the capacitors **C3** through **C10**. In one embodiment, with this value set at 51K ohms, the maximum counting rate is 150 pulses per second. In another embodiment, with the value being 33K ohms, this counting rate was increased to 200 pulses per second.

Instead of utilizing an indicating lamp as the cathode load of the SCS's a D.C. relay could be substituted which would function to open or close a set of contacts in some other extraneous circuit. This embodiment, illustrated in FIGURE 2, shows a diode **D17** being connected across a relay coil **30** to suppress any negative voltage developed across the coil. The relay contacts **31** are shown in some extraneous circuit **32**.

Although the circuit and method of operation has been described in a preferred embodiment, it should be understood that various modifications and other arrangements will be obvious to those skilled in the art. Thus it is not intended that applicant be limited to the embodiment described but rather should be entitled to the full scope of the appended claims.

What we claim as new and desire to secure by Letters Patent of the United States is:

1. A reversible ring counter comprising a plurality of controlled switch stages connected in cascade, each stage capable of being established in either of two discrete conducting states, each of said stages comprising a silicon control switch having an anode gate, a cathode, and an anode; means including a source of supply voltage connected to the anodes of each of said switches for establishing a selected one of said switch stages in a conductive state and the remaining of said switch stages in a non-conductive state; means responsive to an input pulse for shunting said supply voltage away from said anodes to thereby establish said selected conductive switch stage into a non-conductive state; a plurality of load impedances each of said load impedances being connected to the cathode of each respective one of said switches; a plurality of gate resistors each of said gate resistors being connected between said supply voltage source and the anode gate of a respective one of said switches; a plurality of first series circuits each including a diode and a first capacitor connected between the anode gate of each of said switches and the load impedance of an immediately preceding one of said switches; a plurality of second series circuits, each including a second diode and a second capacitor, connecting the anode gate of each of said switches to the load impedance of an immediately succeeding switch, means for determining preselected charging paths for said first and second capacitors, whereby when said selected conductive switch stage is rendered non-conductive by said pulse responsive means, an associated first capacitor charges through said first diode and the gate resistor connected to the anode gate of the immediately adjacent switch to produce a voltage drop across the last mentioned gate resistor to thereby constitute means for establishing

said adjacent switch in a conductive state, and an associated second capacitor simultaneously charges through its preselected charging path maintaining a predetermined one of said switches in a non-conductive state.

2. A reversible ring counter as defined in claim 1, wherein said charging path determining means comprise add and subtract terminals, a plurality of first steering diodes, each connected between said subtract terminal and a respective one of each of said first series circuit, and a plurality of second steering diodes, each connected between said add terminal and a respective one of each of said second series circuit; and means for supplying voltage to either one of said terminals.

3. A reversible ring counter as defined in claim 1, wherein said pulse responsive means comprise a transistor having base and collector electrodes, and means for coupling said input pulse to said base electrode, said collector electrode being connected to the anodes of each of said silicon control switches.

4. A reversible ring counter as defined to claim 1, 20

wherein the time constants of the charging paths of said first and second capacitors are of a sufficient value to permit the charging of said capacitors for a period longer than the duration of said input pulse.
